UNITED STATES PATENT OFFICE

DOUGLAS COLLINS, OF SALISBURY, NORTH CAROLINA

CARBURETOR

Application filed April 22, 1930. Serial No. 446,367.

My present invention relates to improvements in carburetors for use with internal combustion engines employed as motors for automotive vehicles, aircraft, and watercraft, and the invention applies particularly to the air valve or "choke" by means of which the admission of air for diluting the fuel mixture is automatically controlled and governed. In carrying out my invention I utilize motive fluid as pressure from both the exhaust manifold, and suction from the intake manifold, of the engine or motor for automatically controlling the position of the choke or air valve, to govern and regulate the admission of air to the carburetor for delivery to the fuel mixture. The automatically operating air control device, or choke, also depends in some instances and under some conditions, upon the position of the standard throttle valve that controls and governs the admission of the fuel mixture, after carburetion, to the cylinders of the motor.

The choke or air valve is of the gravity operated type, and I utilize a spring or other means, for holding the valve in closed position, in the absence of motive fluid pressure capable of opening the air valve.

As is well known, when the motor of an automotive vehicle is already heated from previous operations of the motor, or during hot weather conditions or other natural causes, a rich fuel mixture is not required for starting the firing of the cylinders. Under such conditions the air valve is automatically opened for the admission of air to dilute the fuel mixture. When the engine or motor is cold, and especially when the motor is exposed to cold weather conditions, a rich fuel mixture is required to fire the cylinders, and after the engine is running smoothly the rich mixture may be diluted. At starting, when the motor is cold and an undiluted mixture is required, the air valve is prevented from opening and diluting the fuel charge because of conditions existing in the valve mechanism due to the open or partly open position of the throttle valve, which latter valve is of course manipulated to permit flow of fuel mixture from the carburetor to the intake manifold.

My invention consists in certain novel combinations and arrangements of parts as will hereinafter be more fully set forth and claimed. As here illustrated, the invention is embodied as an attachment at the air intake portion of the carburetor, and the carburetor illustrated is of conventional type. It will be understood that the automatically operating valve mechanism may form an integral element of a carburetor to which the invention is adaptable. In the accompanying drawings I have illustrated one complete example of the physical embodiment of my invention wherein the parts are combined and arranged according to one mode I have successfully operated for carrying out the principles of my invention.

Figure 1 is a view of a typical motor equipped with the device of my invention.

Figure 2 is an enlarged side view of a standard type of carburetor with which my device is combined.

Figure 3 is a detail view, partly in section, showing the connection to the exhaust manifold for obtaining motive fluid pressure.

Figure 4 is a view in elevation (as seen from the front of the motor) of the automatically operating valve control device.

Figure 5 is a view in elevation at the inner side of the air valve mechanism or choke.

Figure 6 is a vertical sectional view of the device.

In order that the general arrangement and relation of parts may readily be understood, I have shown in Figure 1 a conventional motor or internal combustion engine 1 with the usual fan 2 at the front and the fly wheel 3 at the rear. The intake manifold for feeding the fuel mixture into the engine cylinders is designated as 4, while the exhaust manifold and exhaust pipe are designated by the numeral 5, and connections are made to these manifolds that are instrumental in the automatic operation of the air valve of the carburetor.

A well known type of carburetor is illustrated as attached by its flange 6 to the intake manifold, and the carburetor throat or fuel pipe 7 from the carburetor has therein the usual throttle valve 8, operated by a lever 9

that is pivoted at 10 on the fuel pipe, and manually, or pedal, operated, (or otherwise controlled) by suitable mechanical connections including the pivot rod 11.

5 The float chamber 12 of the carburetor receives liquid fuel from a suitable source of supply, and the fuel therefrom passes through the body 13 of the carburetor to the fuel pipe 7.

10 Air for the fuel mixture is admitted to the carburetor through the air intake pipe 14, and my automatically operating valve control device or choke is mounted on the air intake pipe.

15 The choke device, as an attachment, includes an air chamber 15, and the casing of the chamber is fashioned with an attaching collar 16 which may be cylindrical to fit over the cylindrical air intake pipe, and the device is fastened on the air intake pipe by means of a set bolt 17 or other suitable means.

20 The air valve or choke valve 18 is a flat, light, metal plate adapted to close the open end or air inlet port of the chamber 15, and this valve is secured on a pivot pin 19 that is journaled in a slot 20 in the casing, above the chamber 15. The two projecting ends of the pivot pin are supported or journaled in two oppositely arranged trunnion-bolts 21,

25 and these bolts are threaded and adjustable in the brackets 22 and 23 fashioned integral with or fixed to the outer, opposite sides of the valve-casing. The bolts are adjusted to minimize the friction at the bearing ends 30 of the pivot pin to insure the required freedom of pivotal movement of the valve and pin.

35 A spring 24 is coiled about the pivot pin with its inner end anchored to the pin and its outer end anchored to a clip 25 that is fixed to the casing in proper position for the purpose. The spring has a tendency to close the valve against the inlet port of the air chamber 15, thus preventing admission of air to the carburetor when a rich mixture is desired for the motor.

40 Above the air passage or chamber 15 is fashioned a pressure chamber 26 in which is located a valve lever or pressure plate 27 rigid with the pivot pin 19 and the valve 18, and fixed in a plane parallel with the valve. It will be seen from the dotted lines in Figures 5 and 6 that the valve and pressure plate swing with the pivot pin as a center, 45 under influence of motive fluid pressure imposed against the outer face of the pressure plate. This pressure may be imposed directly by exhaust gases from the exhaust manifold, against the left face of the plate in Figure 6, or when suction is present at the right side of the plate, atmospheric or other pressure is caused to be applied at the left side of the plate, to swing the latter with the valve.

50 A suction tube 28 passes upwardly through

the air chamber 15 and has an open upper end or port 29 in the pressure chamber 26. This suction tube has a nipple, or other suitable joint, coupled to a suction pipe 30 that is attached to the intake manifold of the motor, and the pipe communicates at all times with the interior of the intake manifold. When the pistons create suction in the cylinders, the suction, under some conditions, is sufficient to cause the pressure plate to swing, and open the valve 18, as indicated by dotted lines.

55 To introduce motive fluid pressure from the exhaust manifold to the pressure chamber 26, I utilize a flexible pipe 31 that is attached at one end to the boss 32 located near the top of the casing, and opening into the pressure chamber. The exhaust manifold is provided with a hole or port 33 drilled therein, and a clamp plate, or curved shoe 34 conforming to the shape of the exhaust pipe or manifold, is secured about the ported part of the pipe by means of U-bolts 35, or in other suitable manner. An asbestos packing or gasket 36 is interposed between the clamp plate and the exhaust pipe to prevent escape of gases, and the plate is fashioned with a boss 37 in which a nipple 38, on the flexible pipe, is threaded.

60 It will be apparent that the flow of exhaust gas through the flexible pipe, against the outer face of the pressure plate 27, will tend to swing the plate and the valve on the pivot pin, to open the valve for admission of air to the carburetor.

65 Assuming the engine to be started by the operation of the usual starting motor, or otherwise, with the throttle 8 in its minimum open position and before the exhaust gases are produced by firing in the cylinders, the suction created by the reciprocating pistons extends through the intake manifold to the carburetor, and to the pressure chamber. The suction through the suction pipe 30 from the pressure chamber, however, is greater than the suction through the throat of the carburetor, or the feed pipe 7, because of the fact that the throttle valve is only partially opened, i. e. open to its minimum area.

70 Therefore the suction through pipe 30 permits the motive fluid pressure against the left side of the pressure plate 37 to swing the air valve or choke open, against the tension of the spring, and the valve or choke is held open while the motor is being started, 75 thus admitting air in desired volume to the carburetor. Such operation takes place when the throttle valve is "closed", which is the usual and desirable position for the throttle when a rich mixture is not required for starting the engine. Thus, when the engine is already heated from previous operations, or when the engine is warm due to weather conditions, this described operation of the valve takes place.

If the motor is cold, it is necessary or desirable, to advance or open the throttle valve 8, and thereby admit a larger volume of fuel mixture to the cylinders for starting the engine, and this fuel mixture should be richer than the quality of the fuel mixture employed when the engine is hot. Thus, when the motor is cold, the air valve or choke is required to remain closed against admission of air that would dilute the required rich fuel mixture. Under such conditions the suction pipe 30 and the throat of carburetor, or pipe 7 contain a suction from the engine that is more nearly equalized, due to the fact that the throttle valve is open wider than is required when starting the engine while the latter is hot. The spring 24 therefore holds the choke or air valve closed and prevents dilution of the rich fuel mixture.

After the engine is started and the cylinders are firing smoothly, the speed of the engine creates such a degree of suction as to open the air valve or choke, especially if the throttle has been returned to its minimum open position. With the engine running and the cylinders firing, the pressure of the exhaust gases in the pressure chamber is sufficient to swing open the choke or air valve to admit air to the fuel mixture, and the quality of the fuel mixture is thus properly maintained for efficient running of the engine with a minimum consumption of fuel.

Frequently, after the motor is started, it begins to "spit" indicating that an additional choking is required. This condition is remedied by depressing the throttle pedal or advancing the hand lever of the throttle, to open the throttle 8 (a natural performance under the circumstances) and consequently the suction through the carburetor and through the suction pipe and chamber 26 is equalized. Now if the engine exhaust is weak (due to the fact that the engine is starving for fuel and needs choking) the exhaust will be insufficient to hold the choke valve against the pressure of the spring, and the choke valve will close, thus choking the engine. The cycle of starting is then repeated, so that the choke, when the motor exhaust is weak, will close when the accelerator or foot throttle is depressed, and open when the pedal is released. If, however, the motor, is firing naturally and does not require choking, the exhaust gases will at all times hold the valve, in open position.

It will thus be seen that I have devised a choke which is operated by the pressure of exhaust gases of the engine, assisted and controlled by the intake suction of the engine manifold, and the choke is controlled in its operation by manipulation of the throttle valve of the engine.

The consumption of liquid fuel is thus varied, and the quality of the fuel mixture is

controlled and regulated by the automatic operation of the choke valve, due to the motive fluid pressure as described.

Having thus fully described my invention, what I claim as new and desire to secure by Letters Patent is:—

1. A valve control mechanism comprising a ported air chamber and choke valve therefor, a pressure chamber and a pressure operated lever therein rigid with the valve, means for introducing fluid pressure to the pressure chamber and resilient means for holding the valve in closed position. 75

2. The combination of a valve casing having an air chamber, a pivoted valve for controlling passage of air through said chamber, said casing having a pressure chamber and means for introducing motive fluid to said pressure chamber, a pressure plate in said chamber and rigid with the valve, and a spring for holding the valve in closed position. 80

3. The combination of a valve casing having an air chamber, a pivoted valve for controlling passage of air through said chamber, said casing having a pressure chamber and means for introducing fluid pressure to said chamber, a pressure plate in the pressure chamber and rigid with the valve, and a suction pipe having a port on said pressure chamber. 95

4. In a carburetor for internal combustion engines, the combination of a throttle valve for the intake manifold, a choke valve for the carburetor, a pressure chamber adjacent the choke valve, a suction pipe between the pressure chamber and the manifold, a fluid pressure actuated element rigid with the choke valve and located in the pressure chamber, and means for introducing exhaust gases to the pressure chamber. 100

5. In an air valve mechanism, the combination with a casing having an air passage and a choke valve for controlling admission of air through said passage, said casing having a pressure chamber, a valve-actuating element in the pressure chamber, a suction pipe having a port in the pressure chamber at one side of said element, and a motive fluid pressure pipe having a port to the chamber at the other side of the element. 110

6. In a choke mechanism, the combination with a casing having an air passage and a pivoted choke valve, said casing having a pressure chamber and a valve lever-plate in said chamber, a suction pipe having a port in the pressure chamber at one side of the lever-plate, and an exhaust gas pipe having a port in the pressure chamber at the opposite side of the lever-plate. 120

In testimony whereof I affix my signature.

DOUGLAS COLLINS.
